UNITED STATES PATENT OFFICE.

OSCAR PAUL BREITHUT, OF WILLIAMSPORT, PENNSYLVANIA.

SPRING-FRICTION MIRROR-PIVOT.

SPECIFICATION forming part of Letters Patent No. 325,493, dated September 1, 1885.

Application filed March 30, 1885. (Model.)

To all whom it may concern:

Be it known that I, OSCAR PAUL BREITHUT, of Williamsport, in the county of Lycoming and State of Pennsylvania, have invented a new and Improved Spring-Friction Hinge, of which the following is a full, clear, and exact description.

Reference is to be had to the accompanying drawings, forming part of this specification, in which similar letters of reference indicate corresponding parts in both the figures.

Figure 1 is a side elevation, and Fig. 2 is a vertical transverse section taken on the line xx , Fig. 1.

The object of my invention is to provide an effective spring-friction hinge for hanging mirrors, transom-lights, and for other similar uses.

My invention consists in a slotted base-plate provided with a curved spring adapted to receive the pivot of the mirror or transom-light, and provided with a tightening-screw by means of which the friction on a pivot may be increased or diminished.

For convenience in removing the pivot from the spring I allow one end of the spring to remain free, so that after the removal of the tightening-screw the pivot may be lifted out of its place in the hinge.

The base-plate A is provided with a longitudinal slot, B, and is grooved on its under surface to receive the end of the spring C. The spring C is bent outward at the inner end of the slot B, thence upward toward the upper end of the plate A in a reverse curve, the lower portion forming a loop for receiving the pivot D, the upper portion being turned outward to admit of readily inserting the pivot D between the spring C and the plate A. The plate A is provided with an aperture for receiving the fastening-screw a near the lower

end, and the spring C is apertured above the pivot to receive the screw b , which passes into the supporting-frame of the mirror or transom and serves to draw the spring C around the pivot D, so as to produce more or less friction 45 on the said pivot to cause the frame E which is secured to the pivot to remain in any position, in which it may be placed.

By removing the screw b from the spring C the pivot D may be raised up out of the hinge 50 or replaced therein. It will be seen that by this construction the mirror or transom frame E may readily be lifted by one person, so as to remove the pivots D from the spring C, or to replace them therein, thereby avoiding the 55 difficulty of requiring two persons to place or remove the mirror or transom-light.

I am aware of the existence of a friction-hinge with its leaf constructed of two wings made in a continuous piece and bent around 60 the pintle or pivot, said wings having registering apertures to receive securing-screws or fastenings.

Having thus described my invention, I claim as new and desire to secure by Letters Patent— 65

1. The combination, in a spring - friction hinge, of a slotted base-plate, its means of fastening, a curved apertured spring, and the cylindrical pivot, substantially as and for the purpose set forth.

2. The combination, in a spring - friction hinge, of a slotted and grooved base-plate, A, a curved and apertured spring, C, attached to the base-plate, the screw b , and the cylindrical pivot D, substantially as herein described. 75

OSCAR PAUL BREITHUT.
